W. V. JOHNSON ET AL

CAR FLOOR AND DRAFT GEAR

Filed Dec. 15, 1926

Patented Nov. 15, 1927.

UNITED STATES PATENT OFFICE.

WARREN V. JOHNSON AND ROBERT C. KEPNER, OF BLOOMSBURG, PENNSYLVANIA, AS
SIGNORS TO AMERICAN CAR AND FOUNDRY COMPANY, OF NEW YORK, N. Y., A COR-
PORATION OF NEW JERSEY.

CAR FLOOR AND DRAFT GEAR.

Application filed December 15, 1926. Serial No. 154,954.

In the drawings:

Fig. 1 shows a vertical longitudinal section through one end of a mine car equipped with a draft gear comprising the present invention;

Fig. 2 is a fragmentary bottom plan view of a car, illustrating the mounting of the draft gear;

Fig. 3 is an end view of a car, with the drawhead or coupler in cross section as indicated by the line 3—3 in Fig. 1;

Fig. 4 is a fragmentary plan view similar to Fig. 2, but illustrating a somewhat different construction;

Fig. 5 is a vertical sectional view of the coupler and associated parts, similar to a portion of Fig. 1, but showing the construction of Fig. 4;

Fig. 6 is a fragmentary end view, with the coupler and bumper in section as indicated by the line 6—6 in Fig. 5.

This invention relates to car floor and draft gear construction, being particularly adapted and advantageous for mine cars. A principal object of the invention is to provide a simple, rugged construction, which can be easily and inexpensively manufactured, installed and repaired, and whose parts can be easily duplicated and replaced.

The drawings show the invention applied to a conventional mine car mainly of wooden construction, with a plank flooring 10, side 11, and end 12. As shown in Fig. 1, the car wheel 13 trenches somewhat on the thickness of the floor 10, which accordingly has an opening to accommodate it, with a sheet metal hood 14. Into the floor 10 is set or built a longitudinal center sill 15 of channel cross section. At its lower edges, this channel 15 has outward projecting lateral flanges 16 which are gained into the adjacent planking 10 and secured thereto by bolts 17. In the present instance, the channel 15 corresponds in vertical depth substantially to the thickness of the planking 10, so that its upper surface is flush with that of the rest of the floor. Contributing to the support of the floor 10, along either side of the opening of the channel 15, are longitudinal sill angles 18, 18, each arranged with one of its flanges horizontal and the other depending vertically. As shown in Figs. 2 and 3, the horizontal angle

flanges substantially coincide with the outward extending channel flanges 16, and are secured thereto by rivets 19. In addition, the horizontal angle flanges are also secured to the planking 10 by some of the bolts 17 (Fig. 3). The vertical angle flanges form downward extensions of the channel sides. As shown in Figs. 1, 2 and 3, there is a transverse tie strap 20 beneath the flooring 10 at the end thereof. This is secured to the flooring 10 by bolts 21. As shown in Fig. 1, this strap 20 extends clear across the floor and up outside the car sides to their tops, where its ends are bent inward. In the mid-region of the floor, the strap 20 is offset downward under the ends of the angle sills 18 as best shown in Fig. 3.

The draft gear or drawhead shown in Figs. 1-3 is of a spring buffer type, comprising a double acting helical compression spring 24 in a rectangular metal box 25 open at its bottom, and a coupler 26 with a broad head 27 adapted to take the coupling link 28 and coupling pin 29, and also to serve as a buffer. The box 25 is mounted in the channel 15 and extends downward between the draft sill angles 18, and it is secured to the channel sides and to the vertical angle flanges by rivets 31. The shank of the coupler 26 extends out between the channel sides and the angles 18, 18. As shown in Figs. 1-3, the coupler 26 is supported by a U-shaped carry-iron yoke 32, whose sides are secured to the channel sides and to the vertical angle flanges by rivets 33. The sides of the yoke 32 have inward extending flanges 34 which act as stops to limit the sidewise play of the coupler 26 to a reasonable amount.

As already intimated, the spring 24 is adapted to cushion both tractive pull and buffing shocks. As shown in Figs. 1 and 2, there are flanged sleeves or thimbles 35, 35 mounted in openings in the ends of the box 25, each sleeve with its flange seated inside the box so as to afford a fixed abutment for the spring 24 against inward movement of the other sleeve. For transmitting impacts, the coupler shank 26 bears directly against the adjacent sleeve 35; for transmitting pulls, the coupler is connected to the other sleeve 35 by a bolt 36 extending through both sleeves as well as through the midst

of the spring 24 between them. The bolt head 37 bears against an internal shoulder 38 in the hollow coupler shank 26. The nut 39 on the other end of the bolt is secured by a cotter 40.

The construction shown in Figs. 4-6 differs from that of Figs. 1-3 in that buffering shocks are taken by outward extensions of the car flooring at either side of the sills 15, 18, 18 and of the draft gear. These are provided with angular protective sheathing 41 extending down outside a filler 42 bolted to the lower side of the planking 10 at 42°. The carry-iron of Figs. 1-3 is 15 omitted. The binder strap 20a is interrupted at either side of the vertical sill flanges, and its ends are secured by the bolts 42a through the latter.

The draft gear illustrated in Figs. 4-6 20 inclusive acts only in tension, and accordingly comprises a hook 43 for engaging the coupling link 28. Only one flanged sleeve 35a is provided for the spring 24, at the far end of the box 25a—the other end of the springs abutting directly against the box end around the shank of the coupling hook 43. The end of the coupling hook shank is secured in the sleeve 35a by a vertically arranged flat key 44, with cotters 45, 30 45 in its upper and lower ends.

What is claimed is:

1. In combination with a mine car floor, an inverted longitudinal metal channel sill therein, with the web thereof substantially flush with the upper surface of said floor, of longitudinal metal reinforcing angles at either side of the channel secured thereto.

2. The combination with wooden mine car flooring and an inverted longitudinal metal channel sill therein with outward projecting flanges along its lower edges secured to said flooring, of longitudinal metal angles beneath said flanges secured thereto.

3. The combination with a car floor and an inverted longitudinal metal channel sill therefor, of longitudinal metal draft sills secured to the channel sill sides to form downward extensions thereof, and a drawhead mounted in said channel sill and secured thereto and to said draft sills.

4. The combination with wooden mine car flooring and an inverted longitudinal metal channel sill therein with outward projecting flanges along its lower edges secured to said flooring, of longitudinal metal angles beneath said flanges secured thereto, and a drawhead mounted in said channel sill and secured thereto and to said angles.

5. The combination with wooden mine car flooring and an inverted metal channel sill therein with its sides secured thereto, of longitudinal metal draft sills secured to said flooring and extending downward below the same, and a drawhead mounted in said chan-

nel sill and secured thereto and to the downward extending portions of said draft sills. 65

6. The combination with wooden mine car flooring and an inverted longitudinal metal channel sill therein with outward projecting flanges along its lower edges extending beneath said flooring and secured thereto, longitudinal metal angles beneath said flooring at either side of the channel opening secured to the flooring, with flanges depending therebelow, and a drawhead mounted in said channel secured thereto and to said depending angle flanges. 70

7. The combination with wooden mine car flooring and an inverted longitudinal metal channel sill therein, of longitudinal metal reinforcements secured to the channel sill sides to form downward extensions thereof below the wood flooring, and a transverse metal strength member at the floor end offset downward beneath said reinforcements. 80

8. The combination with a car floor and an inverted longitudinal metal channel sill therefor, of longitudinal metal draft sills secured to the channel sill sides to form downward extensions thereof, a drawhead mounted in said channel sill, and a carry-iron yoke for the coupler mounted in the channel and secured to said draft sills at either side. 90

9. The combination with a car floor and an inverted longitudinal metal channel sill therefor, of longitudinal metal draft sills secured to the channel sill sides to form downward extensions thereof, a drawhead mounted in said channel sill, a carry-iron yoke for the coupler mounted in the channel and secured to said draft sills at either side, and a transverse metal strength member at the floor end offset downward beneath said reinforcements and the coupler. 95

10. In combination with a mine car floor, a center sill comprising an inverted longitudinal channel in said floor with the web thereof flush with the upper surface of the floor, and longitudinal reinforcing angles secured directly to the channel at either side thereof with one portion of said angles in alignment with the sides of the channel. 100

11. In combination with a mine car floor, a center sill comprising an inverted longitudinal channel in said floor with the web thereof flush with the upper floor surface, said channel having outwardly extending attaching flanges, and a longitudinal reinforcing angle secured at one leg directly to 115 each attaching flange with the other leg depending in substantial alignment with the adjacent side of the channel.

In witness whereof we have hereunto set our hands.

WARREN V. JOHNSON.
ROBERT C. KEPNER.
